UNITED STATES PATENT OFFICE.

FRANCIS JOSEPH CLAVELOUX, OF WASHINGTON, DISTRICT OF COLUMBIA.

DESIGN FOR A GAME-BOARD.

46,943.

Specification for Design.

Patented Feb. 16, 1915.

Application filed November 7, 1914. Serial No. 870,919. Term of patent 7 years.

To all whom it may concern:

Be it known that I, FRANCIS J. CLAVELOUX, a citizen of the United States, residing in the city of Washington, in the District of Columbia, have invented a new, original, and ornamental Design for a Game-Board, which is represented in the accompanying drawing, forming part hereof.

The figure represented is a plan view of the game-board showing my new design.

I claim:

The ornamental design for a game-board, as shown.

FRANCIS JOSEPH CLAVELOUX.

Witnesses:

SOLON C. KEMON,
AMOS W. HART.
